UNITED STATES PATENT OFFICE.

GASTON CORBETT LEWIS, OF BAYARD, FLORIDA.

DESIGN FOR AN INSECT-TRAP.

SPECIFICATION forming part of Design No. 32,432, dated April 3, 1900.

Application filed March 2, 1900. Serial No. 7,134. Term of patent 7 years.

To all whom it may concern:

Be it known that I, GASTON CORBETT LEWIS, a citizen of the United States, residing at Bayard, in the county of Duval and State of Florida, have invented and produced a new and original Design for an Insect-Trap, of which the following is a specification.

This invention relates to a new and original design for an insect-trap; and it has for its object to provide a design of this character that shall be both useful and ornamental.

The leading feature of the design resides in the circular concavo-convex shell, having a convexed upper side and an inwardly-curving pendent rim, said rim being curled into a plurality of interior spiral convolutions, with the walls of the convolutions spaced apart.

The minor features of the design are the concavo-convex shell, being provided in the closed top portion thereof with a central opening and also with a single opening eccentrically located.

In the drawings, Figure 1 is a top perspective view of an insect-trap embodying the herein-described design. Fig. 2 is a bottom perspective view thereof. Fig. 3 is a cross-sectional view of the same.

Referring particularly to the drawings, the numeral 1 designates the trap, consisting of 30 a circular concavo-convex shell having a convexed upper side 2 curving directly into a pendent rim portion 3. The pendent rim portion 3 is a direct continuation of the curvature of the top or body portion of the shell 35 and curves in an inward direction, and the said rim is curled into a plurality of interior spiral convolutions which are spaced apart, but each of which convolutions conforms to the general circular shape of the shell. The 40 top portion of the shell is provided with a central circular opening 4 and also with an eccentrically-disposed opening 5, arranged between the pendent flange portion and the central opening 4. 45

What is claimed is—

The design for an insect-trap herein shown and described.

In testimony that I claim the foregoing as my own I have hereto affixed my signature in 50 the presence of two witnesses.

GASTON CORBETT LEWIS.
